[57] CLAIM

The ornamental design for a handle for attachment to a
dental impression tray, as shown and described.

DESCRIPTION

FIG. 1 is a top perspective view of a handle for attachment
to an upper dental impression tray, showing my
new design;

FIG. 2 is a top perspective view of a modified embodiment
of the handle illustrated in FIG. 1, for attachment
to a lower dental impression tray;

FIG. 3 is a side elevation of the embodiment disclosed
in FIG. 2;

FIG. 4 is a side elevation of the embodiment disclosed
in FIG. 1;

FIG. 5 is a top plan view of the embodiment shown in
FIG. 2;

FIG. 6 is a top plan view of the embodiment shown in
FIG. 1;

FIG. 7 is a rear elevation thereof; and

FIG. 8 is a rear elevation of the embodiment disclosed
in FIG. 2.

The broken lines representing the tray are shown for
illustrative purposes only.
